CLAIM

The ornamental design for the fireplace frame, as shown and described.

DESCRIPTION

FIG. 1 is an isometric view of the fireplace frame showing our new design;

FIG. 2 is a front elevation view thereof;

FIG. 3 is a rear elevation view thereof;

FIG. 4 is a right-side elevation view thereof, the left-side elevation view is substantially the same as the right-side elevation view;

FIG. 5 is a top plan view thereof; and,

FIG. 6 is a bottom plan view thereof.

The broken lines, including those showing of portions of the fireplace frame and the interior of a firebox surround, are for illustrative purposes only and form no part of the claimed design.
